Primary Examiner — Darlington Ly(74) *Attorney, Agent, or Firm* — Cowan, Liebowitz & Latman, P.C.; Anastasia Zhadina(57) **CLAIM**

The ornamental design for a hood of an automobile or toy car, as shown and described.

DESCRIPTION

FIG. 1 top, front, and left side perspective view of a hood of an automobile or toy car embodying my new design;
 FIG. 2 is a top, rear, and right side perspective view thereof;
 FIG. 3 is a front elevation view thereof;
 FIG. 4 is a rear elevation view thereof;
 FIG. 5 is a left side elevation view thereof; and,
 FIG. 6 is a top plan view thereof.
 Portions of the automobile or toy car shown in broken lines form no part of the claimed design.
